Application June 30, 1948, Serial No. 36,198

14 Claims. (Cl. 36—2.5)

1

This invention has relation to a shoe.

An object of the invention is to provide a shoe which will be of novel and improved construction.

A further object is to provide a shoe which will include a construction and arrangement for supporting the arch of a person's foot and wherein will be incorporated desirable and improved features and characteristics.

And a further object is to provide a shoe which will include a new and improved construction and arrangement applied to the bottom of the shoe at a location forwardly of the heel and in protecting relation to the arch of the foot of a wearer.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible as long as within the spirit of the invention and the scope of the claims which follow.

In the accompanying drawings forming a part of this specification,

Fig. 1 is a side elevational view of a shoe made according to the invention;

Fig. 2 is a bottom plan view of the shoe of Fig. 1, parts of an attachment device of said shoe being removed or omitted;

Fig. 3 is an enlarged vertical longitudinal sectional view, taken on line 3—3 in Fig. 4, showing the parts of the attachment device which are removed from, or omitted in, the disclosure of Fig. 2;

Fig. 4 is a detail view, partially in section and partially in elevation, taken as on line 4—4 in Fig. 3;

Fig. 5 is an enlarged transverse sectional view of the attachment device, taken on line 5—5 in Fig. 1;

Fig. 6 is a side elevational view of a shoe of modified construction incorporating features and characteristics of the invention;

Fig. 7 is a bottom plan view of the shoe of Fig. 6, a cover strip of the shoe being omitted;

Fig. 8 is a vertical transverse sectional view, taken on line 8—8 in Fig. 6; and

Fig. 9 is a vertical longitudinal sectional view, taken on line 9—9 in Fig. 7.

With respect to Figs. 1 to 5 of the drawings and the numerals of reference thereon, 10 denotes

2

a shoe, as customarily worn by football players, having cleats 11 on the sole 12 and cleats 13 on the heel 14 of the shoe, and 15 represents an attachment device for said shoe, applied to the sole and heel between the cleats 11 and 13, beneath the arch and in protecting relation to the foot of a wearer.

A metal plate 16 of the attachment device 15, secured, as by screws 17, to the sole and heel of the shoe between the cleats 11 and 13, integrally or rigidly supports spaced apart, downwardly extending flanges 18, 18 situated in vertically alined relation with the opposite side edges of the sole 12 and heel 14 and terminating at their lower side edges at elevation considerably above the lower ends of said cleats 11 and 13. In the disclosed embodiment of the invention, the lower side edges of the spaced apart, downwardly extending flanges 18, 18, terminate in a plane substantially parallel with the plane of the sole 12 and the heel 14 of the shoe.

A compressible rectilinear pad 19, which desirably can be constituted as sponge rubber, is adapted to be situated between the spaced apart, downwardly extending flanges 18, 18 in such manner that its upper surface 20 is engaged against the lower surface of the metal plate 16, its opposite side surfaces 21, 21 are contiguous with internal surfaces of said spaced apart, downwardly extending flanges 18, 18, its opposite end surfaces 22, 22 are in vertically alined relation with the opposite ends of said metal plate 16 and in adjacent relation to cleats 11 and 13, respectively, and its lower surface 23 is situated in a plane disposed considerably below the plane of the lower side edges of the spaced apart, downwardly extending flanges 18, 18 and slightly above and substantially in parallel relation with the plane of the lower ends of the cleats 11 and 13.

The upper surface 20 of the compressible rectilinear pad 19 is cut away to provide spaced apart upwardly opening pockets or concavities 24, five as shown, disposed thicknesswise of said compressible rectilinear pad in perpendicular relation to its upper and lower surfaces and having their lower ends 25 terminating in adjacent relation to the lower surfaces 23. In the illustrated embodiment of the invention the pockets or concavities 24 are of cylindrical configuration, and each pocket or concavity 24 more or less loosely contains a compression coil spring 26 having its lower end engaged against a metallic disc 27 in the bottom of the corresponding pocket or concavity and its upper end adapted to be engaged against the lower surface of the metal plate 16.

Each metallic disc 27 includes an aperture 28 therein for passage of air.

Spaced apart, transversely extending tubes 29, 29 of rigid material desirably metal, imbedded in said compressible rectilinear pad and open at their opposite ends to the opposite side surfaces 21, 21, are for snugly receiving cross rods 30, 30, which also desirably may be of metal, for securing the compressible rectilinear pad to the downwardly extending flanges 18, 18 of said metal plate 16. The transversely extending tubes 29, 29 are adapted to be alined with spaced apart openings 31, 31 through said downwardly extending flanges, and each cross rod 30 is adapted to be snugly inserted through alined openings 31, 31 in the downwardly extending flanges, as well as through the transversely extending tube 29 at the corresponding end of said compressible rectilinear pad. Each cross rod 30 has a retaining head 32 on one of its ends and a transverse aperture 33 in its opposite end portion adapted to removably receive a transverse retaining pin 34. The retaining heads 32, 32 and the retaining pins 34, 34 desirably will be in contiguous relation with the exterior surfaces of the downwardly extending flanges 18, 18, about as disclosed in Fig. 5 of the drawing, when the cross rods 30, 30 are in their inserted positions, and the opposite ends of the transversely extending tubes 29, 29 will be in contiguous relation with the interior surfaces of said downwardly extending flanges when the compressible rectilinear pad 19 is in secured position. The spaced apart, transversely extending tubes 29, 29, are, as shown, in an upper portion of said compressible rectilinear pad in somewhat spaced relation to its opposite end surfaces 22, 22, respectively, and in clearing relation to the pockets or concavities 24, and the openings 31, 31 for receiving the cross rods 30, 30 are at about the midwidths of the downwardly extending flanges 18, 18. It will be apparent that the compressible rectilinear pad 19 will be retained against transverse movement relative to the shoe by the downwardly extending flanges 18, 18 and against longitudinal movement relative to said shoe by cooperative action of the cross rods 30, 30 and the transversely extending tubes 29, 29.

When a wearer of the shoe is standing so that the lower ends of the cleats 11 and 13 rest on top of a supporting surface, such as the ground, for said shoe, the lower surface 23 of said compressible rectilinear pad 19 will be in spaced relation to the shoe supporting surface, and when said cleats 11 and 13 become imbedded in said shoe supporting surface a distance equal to a measurement representing the distance said lower surface 23 is spaced from the lower ends of the cleats 11 and 13, the compressible rectilinear pad itself will be in engagement with the shoe supporting surface. The construction and arrangement will be such that the compressible rectilinear pad and the compression coil springs 26, together, and without aid of the cleats, will withstand the weight of a standing wearer without collapsing of said compression coil springs, and also such that the compression coil springs will become collapsed, to greater or less extent, when the wearer walks, runs or jumps. For heavier individuals, the compression coil springs 26 will be made stronger, or more powerful, than for lighter individuals.

The attachment device functions as an arch supporter and protector for the foot and ankle of a wearer both when the collapsible rectilinear pad 19 is spaced from the shoe supporting surface 75

and the coil springs 26 are under normal compression and is engaged with the shoe supporting surface and said coil springs are under additional or abnormal compression due to the weight of a wearer, and when said compressible rectilinear pad 19 is placed under additional or abnormal compression so that the coil springs are caused to become collapsed, reaction of said coil springs is upwardly directly beneath the arch of the foot 10 in amount commensurate with the extent of compression of the coil springs. Thus, upward reaction against the arch of a wearer's foot is calculated to counteract in substantial amount tendency toward downward movement or action of the arch of the foot of a wearer when he walks, runs or jumps. When under normal compression, as well as when under additional or abnormal compression, the coil springs 26 function to have tendency toward maintaining the sole 12 and the heel 14 of the shoe substantially in a single plane.

The attachment device, while offering no interference to proper functioning of the cleats 11 and 13, prevents said cleats from becoming imbedded to excessive extent in a supporting surface, such as the ground, for the shoe. Hence, said attachment device is insurance against stumbling as sometimes occurs by reason of football shoe cleats as heretofore employed becoming unduly imbedded in the ground.

30 Referring to Figs. 6 to 9, 40 denotes an ordinary shoe, and 41 represents a construction and arrangement, for the same general purpose as the attachment device 15, beneath the arch and in protecting relation to the foot. The entity 41 is situated between a sole 42 and a heel 43 of the shoe, and said sole and heel are composed principally of cork. More explicitly, there is an insole 44 to which an upper, above the insole, and the sole 42 and the heel 43, below said insole, are secured in such manner as to provide a usual concavity 45 between said sole and heel.

45 A compressible rectilinear pad 46, of sponge rubber as disclosed, is situated and suitably housed in the concavity 45 in such manner that its upper surface is engaged against the lower surface of the insole 44, its opposite side edges are adjacent and within the confines of the opposite side margins of the shoe, its opposite end surfaces 47, 47 are in contiguous relation with the sole 42 and the heel 43, respectively, and its lower surface 48 is situated substantially in the plane of the lower surfaces of the cork portions of said sole and heel. The opposite sides of the compressible pad 46, and the opposite sides and ends 50 of the sole and heel, are enclosed by covering material 49, and a cover strip 50 extends along the lower surfaces of said compressible pad and said sole and heel throughout the whole of the areas of the compressible pad and sole and heel. The construction and arrangement will be such that all of the parts of the shoe are retained together in a unitary structure.

60 The compressible pad 46 is cut away to provide spaced apart openings 51, five as shown, extending thicknesswise through said compressible pad substantially in perpendicular relation to the insole 44. Each opening 51 more or less loosely contains a compression coil spring 52 having its lower end engaged against the cover strip 50 and its upper end engaged against said insole.

65 When a wearer of the shoe is standing, the lower surface of the cover strip 50 beneath the compressible pad 46 will be in slightly spaced relation to the shoe supporting surface, and when the wearer walks or runs said lower surface of

said cover strip beneath said compressible pad may or may not become engaged with the shoe supporting surface. The construction and arrangement will be such that the compressible pad 46 and the compression coil springs 52, together, and without aid from other source, will withstand the weight of a standing wearer of the shoe without collapsing of said compression coil springs, and also such that the compression coil springs will become collapsed, to greater or less extent, when the wearer walks, runs or jumps.

The construction and arrangement which the embodiment of the invention as disclosed in Figs. 6 to 9 incorporates functions as an arch supporter and protector for the foot and ankle of a wearer in the same general manner as does the attachment device 15, both when the collapsible pad 46 is not resting upon the shoe supporting surface and the coil springs 52 are under normal compression and the lower surface of the portion of the cover strip 58 beneath said collapsible pad is engaged with the shoe supporting surface and said coil springs are under additional or abnormal compression due to the weight of a wearer. When the collapsible pad 46 is placed under additional or abnormal compression so that the compression coil springs 52 are caused to become partially collapsed, reaction of said compression coil springs is upwardly directly beneath the arch of the foot in amount commensurate with the extent of compression of the coil springs. As in the instance of the football shoe, upward reaction against the arch of a wearer's foot is intended to counteract in substantial amount tendency toward downward movement or action of the arch of the foot of the wearer when he walks, runs or jumps. When under normal compression, as well as when under additional or abnormal compression, the coil springs 52 function to have tendency toward maintaining the sole 42 and the heel 43 of the shoe substantially in a single plane.

What is claimed is:

1. A shoe including a sole and a heel, a compressible pad secured against and extending downwardly from a bottom surface of said shoe between said sole and heel, a lower surface of said compressible pad terminating substantially in the plane of lower surfaces of said sole and heel, compression coil springs in said compressible pad disposed substantially in perpendicular relation to said lower surfaces of said sole and heel, and means retaining said compression coil spring in said compressible pad.

2. A shoe including a sole and a heel, a compressible pad secured against and extending downwardly from a bottom surface of said shoe between said sole and heel, a lower surface of said compressible pad terminating substantially in the plane of lower surfaces of said sole and heel, compression coil springs in said compressible pad disposed substantially in perpendicular relation to said lower surfaces of said sole and heel, and a cover strip engaged against a lower surface of said compressible pad, said sole and said heel.

3. The combination with a shoe including a sole and heel each supporting cleats, of an attachment device for said shoe comprising a compressible pad secured against and extending downwardly from a bottom surface of said shoe between cleats on said sole and heel, respectively, a lower surface of said compressible pad terminating in spaced relation to and above lower ends of said cleats, and compression coil springs in

5 said compressible pad disposed substantially in perpendicular relation to said bottom surface.

4. The combination with a shoe including a sole and heel each supporting cleats, of an attachment device for said shoe comprising a compressible pad secured against and extending downwardly from a bottom surface of said shoe between cleats on said sole and heel, respectively, a lower surface of said compressible pad terminating in spaced relation to and above lower ends of said cleats, and compression coil springs in said compressible pad disposed substantially in perpendicular relation to said bottom surface, each of said compression coil springs having its lower end situated in adjacent relation to a lower portion of said pad and its upper end engaged against the bottom of said shoe.

5. The combination with a shoe including a sole and heel each supporting cleats, of an attachment device for said shoe comprising a compressible pad secured against and extending downwardly from a bottom surface of said shoe between cleats on said sole and heel, respectively, an upper surface of the compressible pad including downwardly extending pockets and a lower surface of said compressible pad terminating in spaced relation to and above lower ends of said cleats, and compression coil springs in said pockets having their lower ends engaged against base walls of the pockets adjacent the lower surface of the compressible pad and their upper ends engaged against the bottom surface of said shoe.

6. The combination with a shoe including a sole and heel each supporting cleats, of an attachment device for said shoe comprising a compressible pad secured against and extending downwardly from a bottom surface of said shoe between cleats on said sole and heel, respectively, an upper surface of the compressible pad including downwardly extending pockets and a lower surface of said compressible pad terminating in spaced relation to and above lower ends of said cleats, discs in said pockets supported by base walls of the pockets adjacent the lower surface of the compressible pad, and compression coil springs in said pockets having their lower ends engaged against said discs and their upper ends engaged against the bottom surface of said shoe.

7. The combination with a shoe including a sole and heel each supporting cleats, of an attachment device for said shoe comprising a compressible pad having an upper surface secured against a bottom surface of said shoe between cleats on said sole and heel, respectively, and a lower surface in spaced, substantially parallel relation to said upper surface situated above lower ends of said cleats, said upper surface of the compressible pad including downwardly extending pockets, discs in said pockets supported by base walls of the pockets adjacent said lower surface of said compressible pad, and compression coil springs in said pockets having their lower ends engaged against said discs and their upper ends engaged against the bottom surface of said shoe.

8. The combination with a shoe including a sole and heel each having cleats, of an attachment device for said shoe comprising a plate secured against a bottom surface of said shoe between cleats on said sole and heel, respectively, a compressible pad secured against said plate and extending downwardly therefrom, an upper surface of the compressible pad including down-

wardly extending pockets and a lower surface of said compressible pad terminating in spaced relation to and above lower ends of said cleats, and compression coil springs in said pockets having their lower ends engaged against lower walls of the pockets adjacent the lower surface of the compressible pad and their upper ends engaged against said plate.

9. The combination with a shoe including a sole and heel each having cleats, of an attachment device for said shoe comprising a plate secured against a bottom surface of the shoe between cleats on said sole and heel, respectively, a compressible pad secured against said plate and extending downwardly therefrom, a lower surface of said compressible pad terminating in spaced relation to and above the lower ends of said cleats, and compressible coil springs in said compressible pad disposed substantially in perpendicular relation to said plate, each of said compression coil springs having its lower end situated in adjacent relation to a lower portion of said compressible pad and its upper surface engaged against a lower surface of said plate.

10. The combination with a shoe including a sole and heel each having cleats, of an attachment device for said shoe comprising a plate secured against a bottom surface of the shoe between cleats on said sole and heel, respectively, a compressible pad having an upper surface secured against said plate and a lower surface in spaced, parallel relation to said upper surface situated above lower ends of said cleats, said upper surface of the compressible pad including downwardly extending pockets, discs in said pockets supported by base walls of the pockets adjacent said lower surface of said compressible pad, and compression coil springs in said pockets having their lower ends engaged against said discs and their upper ends engaged against said plate.

11. The combination with a shoe including a sole and heel each having cleats, of an attachment device for said shoe comprising a plate secured against a bottom surface of the shoe between cleats on said sole and heel, respectively, spaced apart, downwardly extending flanges on said plate, a compressible pad against said plate between and extending downwardly to position below said downwardly extending flanges, a lower surface of said compressible pad terminating in spaced relation to and above lower ends of said cleats, spaced apart, transversely extending tubes in said compressible pads, cross rods in said transversely extending tubes and in spaced apart, oppositely disposed openings in said downwardly extending flanges securing said compressible pad to said plate, and compression coil springs in said compressible pad disposed substantially in perpendicular relation to said plate, each of said compression coil springs having its lower end situated in adjacent relation to a lower portion of said compressible pad and its upper end engaged against a lower surface of said plate.

12. The combination with a shoe including a sole and heel each having cleats, of an attachment device for said shoe comprising a plate secured against a bottom surface of said shoe between cleats on said sole and heel, respectively, spaced apart, downwardly extending flanges on said plate, a compressible pad against said plate between and extending downwardly to position below said downwardly extending flanges, a lower surface of said compressible pad terminating in spaced relation to and above lower ends of said cleats, spaced apart, transversely extending tubes in said compressible pad and having their opposite ends contiguous with said downwardly extending flanges, cross rods in said transversely extending tubes and in spaced apart, oppositely disposed openings in said downwardly extending flanges securing said compressible pad to said plate, an upper surface of the compressible pad including downwardly extending pockets, and compression coil springs in said pockets having their lower ends engaged against lower walls of the pockets adjacent the lower surface of the compressible pad and their upper ends engaged against said plate.

13. The combination with a shoe including a sole and heel each having cleats, of an attachment device for said shoe comprising a plate secured against a bottom surface of the shoe between cleats on said sole and heel, respectively, spaced apart, downwardly extending flanges on said plate, a compressible pad having an upper surface engaged against said plate, side surfaces contiguous with said downwardly extending flanges and a lower surface in spaced, parallel relation to said upper surface situated below lower edges of said downwardly extending flanges and above lower ends of said cleats, means securing said compressible pad to said plate, said upper surface of the compressible pad including downwardly extending pockets, and compression coil springs in said pockets having their lower ends engaged against base walls of the pockets adjacent said lower surface of said compressible pad and their upper ends engaged against said plate.

14. The combination as specified in claim 13 wherein said means securing the compressible pad to the plate is constituted as spaced apart, transversely extending tubes in said compressible pad and having their opposite ends contiguous with said downwardly extending flanges and cross rods in said transversely extending tubes and in spaced apart, oppositely disposed openings in said downwardly extending flanges.

SAMUEL ISRAEL.
